UNITED STATES PATENT OFFICE.

CHARLES E. RAMÉE, OF NEW YORK, N. Y.

LINE CLAMP.

Application filed December 1, 1927. Serial No. 236,957.

This invention relates to line clamps and particularly to devices of this class for use in connection with clothes lines and like devices; and the object of the invention is 5 to provide a clamp of the class specified which is simple in construction and yet positive and automatic in its operation to lock a line in predetermined positions of adjustment; a further object being to 10 provide a line clamp of the class specified, with means for releasing the lock member thereof in a simple and effective manner to facilitate the adjustment of the clamp without the exertion of undue stress or 15 strain; a further object being to provide a device of the class specified, which is compact in structure and which may be composed of sheet metal parts riveted or otherwise secured together to form a unitary 20 structure; and with these and other objects in view, the invention consists in a device of the class and for the purpose specified, which is simple in construction, efficient in use, and which is constructed as hereinafter 25 described and claimed.

The invention is fully disclosed in the following specification, of which the accompanying drawing forms a part, in which the separate parts of my improvement are 30 designated by suitable reference characters in each of the views, and in which:—

Fig. 1 is a sectional view of a clamp made according to my invention and illustrating the method of its use.

Fig. 2 is bottom view of the structure shown in Fig. 1 with the line omitted; and,

Fig. 3 is a perspective view of a modified form of construction which I employ.

In Figs. 1 and 2 of the drawing, the line clamp is composed of a unitary body consisting of elliptical side wall members 10 and 11, joined together at one end by a web portion 12, and adjacent one side by another web portion 13 having a rounded edge 45 14, note Fig. 1, said web portion spacing the side walls 10 and 11 to form a chamber 15 therebetween, into and through which the clothes line or the like 16 is free to pass. One end of the line is secured to the clamp 50 by its passage around the web 12 and being knotted as seen at 17, while the other end of the line is retained in connection with the clamp by an automatically and manually actuated lock member 18 pivotally supported within the chamber 15 on a pivot pin 19, the inner end of the lock member 18 extend-

ing to form a rounded nose portion 20, around which a line 16 is looped as seen in Fig. 1 of the drawing, and the under side of the lock 18 is offset to form a recess 21 60 and a projecting pawl or prong 22 which cooperates with the web 13 to crimp and wedge the line 16 as seen at 23 in Fig. 1 of the drawing. The lock member 18 has a projecting finger piece 24 which extends 65 well beyond the body of the clamp and which when raised upwardly as viewed in Fig. 1 of the drawing, will release the line 16 to any desired extent, whereas the line 16^a of the line may be pulled through the 70 clamp for tightening purposes, and when released will automatically be locked by the movement of the pawl or prong 22 into engagement therewith, crimping the same as at 23. This action takes place by virtue of the 75 upward stress on the rounded nose portion 20 of said lock member.

In Fig. 3 of the drawing, I have shown a slight modification wherein the body structure of the clamp instead of being molded 80 or integrally formed as in Figs. 1 and 2, is fashioned from two similarly formed disks of sheet metal 25, and these disks are spaced apart to form a chamber therebetween, similar to the chamber 15 by spacing members 27 and 28 riveted or otherwise secured to the separate plates 25. The member 27 serves the purpose of the member 12, and the member 28, the purpose of the member 13. In the structure shown in Fig. 3 of the 85 drawing, the lock member employed will be the same as that shown in Figs. 1 and 2, and the pin 19 thereof will pass through and be mounted in apertures 29 in the plates 25.

From the foregoing, it will be seen that by virtue of the simplicity of the construction of my improved clamp, the same may be produced at a very nominal cost and yet a clamp having very effective and positively functioning clamping properties, and one which may be readily released, notwithstanding the stress or strain thereon or on the line in connection with which the same is employed. The recess 21 and projecting 95 prong 22 forms in conjunction with the members 13—28, a very positive lock, held in position by the stress on the nose portion 20 of the lock member 18. While I am aware of other devices of the general character of my invention, they all fail to accomplish the desired result in a practical fashion 100 105 110

by virtue of the nature of the construction of such devices, and the awkwardness and impracticability in their manner of operation.

5 While I have shown a certain form of construction in the production of my clamp, I am not necessarily limited in this respect, and changes therein and modifications thereof may be made within the scope of the appended claims, without departing from the 10 spirit of my invention or sacrificing its advantages.

Having fully described my invention, what I claim as new and desire to secure by Letters Patent, is:—

1. A line clamp of the class described comprising similarly formed and oppositely disposed side walls with a chamber therebetween, a pawl lock member pivotally supported within and between the side walls of said clamp and having a projecting prong-like part adapted to cooperate with a fixed member bridging the walls of said clamp to crimp and secure one end portion of a line 20 against displacement from said clamp, the inner end of said lock member having a rounded nose portion, around which said end of the line is looped and by means of which said prong is moved into operative position.

2. A line clamp of the class described comprising similarly formed and oppositely disposed side walls with a chamber therebetween, a pawl lock member pivotally supported within and between the side walls of said clamp and having a projecting prong-like part adapted to cooperate with a fixed member bridging the walls of said clamp to crimp and secure one end portion of a line 30 against displacement from said clamp, the inner end of said lock member having a rounded nose portion, around which said end of the line is looped and by means of which said prong is moved into operative position, and the other end of said lock member projecting through the clamp body to form a finger piece, by means of which the lock member 40 may be moved into position to release said end of the clothes line, and means for securing the other end of the line to said clamp body.

45

3. A line clamp of the class described comprising similarly formed and oppositely disposed side walls with a chamber therebetween, a pawl lock member pivotally supported within and between the side walls of the clamp and having a projecting prong-like part adapted to cooperate with a fixed member bridging the walls of said clamp to crimp and secure one end portion of a line 50 against displacement from said clamp, the inner end of said lock member having a rounded nose portion, around which said end of the line is looped and by means of which said prong is moved into operative position, the other end of the lock member projecting through the clamp body to form a finger piece, by means of which the lock member 55 may be moved into position to release said end of the clothes line, and means for securing the other end of the line to said clamp body.

4. A line clamp of the class described comprising similarly formed and oppositely disposed side walls with a chamber therebetween, a pawl lock member pivotally supported within and between the side walls of said clamp and having a projecting prong-like part adapted to cooperate with a fixed member bridging the walls of said clamp to crimp and secure one end portion of a line 60 against displacement from said clamp, the inner end of said lock member having a rounded nose portion, around which said end of the line is looped and by means of which said prong is moved into operative position, the other end of the lock member projecting through the clamp body to form a finger piece, by means of which the lock member 65 may be moved into position to release said end of the clothes line, and means for securing the other end of the line to said clamp body.
